FLEXIBLE-BASE JACK.

1,346,847.

Specification of Letters Patent. Patented July 20, 1920.

Application filed June 9, 1919. Serial No. 302,860.

To all whom it may concern:

Be it known that we, CHARLES W. RIPSCH and JAMES C. DAWLEY, citizens of the United States, residing at Dayton, in the county of Montgomery and State of Ohio, have invented certain new and useful Improvements in Flexible-Base Jacks, of which the following is a specification, reference being had therein to the accompanying drawing.

10 This invention relates to lifting jacks and more particularly to that type of jack in which the standard is pivotally connected with the base.

15 One object of the invention is to provide such a jack in which the standard will be so connected with the base as to form a very strong durable construction, which will not be distorted by the severe strains to which

20 it is subjected in service.

A further object of the invention is to provide such a jack having an improved latch which can be easily operated to release the standard for pivotal movement.

25 A further object of the invention is to provide in such a jack an operating device for the lifting element which can be easily manufactured and assembled with the standard.

30 In the accompanying drawings Figure 1 is a front elevation of a lifting jack embodying our invention, partly in section; Fig. 2 is a side elevation of such a jack; and Fig. 3 is a section taken on the line 3—3 of

35 Fig. 2.

In these drawings we have illustrated one embodiment of our invention and have shown the same as applied to a lifting jack of that type commonly known as a pole jack,

40 that is, a jack for withdrawing telephone poles and the like from the ground. It will be understood, however, that this particular form of jack has been chosen for the purposes of illustration only and that the invention can be applied either in part or in its

45 entirety to jacks of various kinds, and particularly to what are known as emergency jacks.

As here shown, the jack comprises a base

50 1 which is provided with a pair of upwardly extending lugs 2 rigidly secured thereto and preferably formed integral therewith. These

lugs are spaced some distance apart and are of a very strong rigid construction. Mounted on the base is an upright standard 3 comprising side members 4 having at their lower ends bearing lugs or ears 5 which extend between the bearing lugs 2 of the base and are pivotally connected to those lugs by means of pins 6. The pins 6 serve merely to connect the standard with the base and they do not carry the weight of the standard and its load. The weight of the load is transmitted directly from the standard to the base and, to this end, the upper edges of the bearing lugs 2 of the base are curved about the axis of the pivot pins 6 and constitute bearing surfaces. Each side member of the standard is provided with an outwardly projecting flange 7, the lower surface of which is curved about the axis of the pins 6 and rests upon the bearing surface of the corresponding lug 2, and these bearing surfaces transmit the thrust directly from the standard to the bearing lugs of the base, and at the same time permit the standard to move freely about the axis of the pivot pin 6 so that the standard can be tilted, either in order to place the same under the load or after it has received the

80 load. By this arrangement of the bearing lugs of the standard within the bearing lugs of the base, the former are held rigidly against any tendency to spread, due to the strains to which they are subjected in service. Where the standards of jacks of this type are of such a character that the bearing lugs of the base are placed between the side members thereof, there is a tendency to spread or to be otherwise distorted. Further, this construction is such that the lugs on the base can be made of a very strong rigid construction; and further, it results in the placing of the bearing surfaces on the outer sides of the side members of the standard instead of between these side members, and thus renders these surfaces very easily accessible for machining and very materially reduces the labor and, consequently, the cost of production of the jack.

100 The standard is retained normally in its upright position by means of a suitable latch which is here shown as a dog 8 pivotally mounted on the base and having its

nose arranged to engage a shoulder 9 on the lower portion of the standard and to hold the standard against movement about the axis of the pivot pins 6. This dog has connected therewith an operating member or foot piece 10 which is acted upon by a spring 11 to hold the dog normally in engagement with the lug 9. This foot piece is so arranged as to be easily manipulated by the operator while both hands are otherwise occupied, and adds very materially to the convenience and ease of the operation of the jack, particularly where the standard is to be swung about its axis when under load.

15 Mounted within the standard 3 is a lifting member 12 which may be of any suitable character, but is here shown as provided along one edge with teeth 13. Coöperating with these teeth is a toothed segment 14 which is pivotally mounted between bearing lugs 15 on the standard and is connected with a lever 16, by means of which it is operated to impart movement to the toothed lifting member or rack bar. The pinion is so mounted on the standard that upon the downward movement of the lever the toothed segment will engage the teeth of the rack and impart upward movement to the latter. Upon the upward or idle stroke of the lever the teeth of the segment will ride over the teeth of the rack, forcing the segment bodily away from the rack, thus permitting the segment to engage other teeth farther down on the rack. A dog 17 holds the lifting member in its elevated position and prevents the rearward movement thereof during the idle stroke of the lever. The segment 14 preferably has its trunnions 18 formed integral therewith, and the bearings for these trunnions are in the form of upwardly and rearwardly inclined slots 19 which are open at their upper ends so that the device may be assembled by merely placing the segment between the bearings lugs 15 and permitting the trunnions to move downwardly in the open ended slots. Pins 20 are driven through the upper ends of the slots to retain the trunnions therein. This construction of the segment very greatly cheapens the production of the jack, inasmuch as the one piece structure can be manufactured and assembled with much less labor than can a two piece construction, in which the two parts are made separately and assembled after the segment has been placed in position between the bearings lugs. Further, such a device has much greater strength than has the two piece construction. This construction also permits the pitch radius of the segment to be made smaller without weakening the structure than is practical in other constructions, thereby affording a more powerful leverage.

60 While we have shown and described one embodiment of our invention we wish to be

understood that we do not desire to be limited to the details thereof, as various modifications may occur to a person skilled in the art.

Having thus fully described our invention, what we claim as new and desire to secure by Letters Patent is:

1. In a lifting jack, a base having a pair of short upwardly extending lugs provided with bearing surfaces along their upper edges, a standard comprising side members having a guideway between them, each of said side members terminating at its lower end in a lug, the lugs of said standard being arranged between the lugs of said base, pivot pins to connect the lugs of said standard to the lugs of said base, each of said side members having on its outer side a shoulder forming a bearing surface to coöperate with the bearing surface of the corresponding lug on said base to support the load on said standard, said bearing surfaces being curved about the axis of said pivot pins to permit said standard to have pivotal movement relatively to said base, a lifting member mounted in said guideway between said side members and an operating device mounted on said standard to actuate said lifting member.

2. In a lifting jack, a base having a pair of short upwardly extending lugs provided with bearing surfaces along their upper edges, a standard comprising side members having a guideway between them, each of said side members terminating at its lower end in a lug, the lugs of said standard being arranged between the lugs of said base, pivot pins to connect the lugs of said standard to the lugs of said base, each of said side members having on its outer side a shoulder forming a bearing surface to coöperate with the bearing surface of the corresponding lug on said base to support the load on said standard, said bearing surfaces being curved about the axis of said pivot pins to permit said standard to have pivotal movement relatively to said base, a lifting member mounted on said guideway between said side members, an operating device mounted on said standard to actuate said lifting member, a latch mounted on said base to engage a part of said standard to hold the latter against pivotal movement, and a downwardly movable tripping device for said latch.

3. In a lifting jack, a base having a pair of upwardly extending lugs provided with bearing surfaces along their upper edges, a standard having bearing surfaces to coöperate with the bearing surfaces of said lugs to support the load on the standard and having lugs extending downwardly beside the lugs on said base, pivot pins to attach said standard to said base, a lifting member having teeth along one edge thereof, a toothed

segment adapted to mesh with the teeth of the said lifting member and having trunnions formed integral therewith, and a lever connected with said segment, said 5 standard having bearing lugs to receive said segment between them and provided with bearing slots which are open at their upper

ends to receive the respective trunnions of said segment.

In testimony whereof, we affix our signatures hereto.

CHARLES W. RIPSCH.
JAMES C. DAWLEY.
